UNITED STATES PATENT OFFICE.

ANTON A. RUEGG, OF SAN FRANCISCO, CALIFORNIA.

INTERNAL-COMBUSTION ENGINE.

1,120,979.

Specification of Letters Patent. Patented Dec. 15, 1914.

Application filed March 25, 1913. Serial No. 756,687.

To all whom it may concern:

Be it known that I, ANTON A. RUEGG, a citizen of the United States, residing at San Francisco, in the county of San Francisco and State of California, have invented new and useful Improvements in Internal-Combustion Engines, of which the following is a specification.

This invention relates to an internal combustion engine of the two-cycle type.

It is the object of this invention to provide an engine of the type in which an inflammable vapor or explosive mixture is compressed and exploded in a cylinder above a piston to reciprocate the latter, and to provide means by which the explosive mixture will be drawn continuously from the carbureter when the engine is in operation.

20 A further object is to provide an internal combustion engine in which four cylinders comprise a unit; and to so form or shape the pistons therein, and so arrange or place the inlet ports opening to the interior of the cylinders and connecting with a carbureter, that gases will be drawn from the carbureter continuously and heated in one cylinder before being introduced into the explosion chamber of another cylinder.

30 A further object is to provide a two-cycle internal combustion engine of high efficiency and capable of being operated at variable speeds or at either a high or a low speed; and which will operate only in one direction and thereby obviate accidental reversal.

Another object is to provide an internal combustion engine having no timing valves or small working parts, and in which a thorough scavenging of the burned gases and a complete recharging of the combustion chambers will be obtained; and in which the compression of the charge in the crank-case or elsewhere other than in the explosion chamber is obviated.

40 Another object is to provide an engine of the above character which is simple in construction and readily assembled, and which is positive and reliable in its operation.

50 Other objects will appear hereinafter.

The invention primarily resides in a series of four engine cylinders, each containing a double piston; the pistons in the cylinders connecting with a crank-shaft; and in the arrangements and connections of the inlet ports of the cylinders with each other.

and the carbureter, by means of which, the explosive mixture will be drawn continuously from the carbureter and be delivered successively to the explosive chambers of the engine cylinders.

The invention further consists of the parts and the construction and combination of parts as hereinafter more fully described and claimed, having reference to the accompanying drawings, in which—

Figure 1 is a vertical section of one of the engine cylinders. Fig. 2 is a horizontal section on the line *a—a* of Fig. 1. Fig. 3 is a horizontal section on the line *b—b* of Fig. 1. Fig. 4 is a horizontal section on the line *c—c* of Fig. 1. Fig. 5 is a horizontal section on the line *d—d* of Fig. 1. Fig. 6 is a plan view of the upper end of a piston, showing the deflector construction. Fig. 7 is a plan view of the engine. Figs. 8, 9, 10 and 11 are diagrams illustrating the four pistons of the engine in one cycle of operation. Fig. 12 is a vertical section on the line *e—e* of Fig. 7. Fig. 13 is a vertical section on the line *f—f* of Fig. 7.

In carrying out the present invention it is necessary to employ four engine cylinders, which may be arranged in any suitable position in relation to each other, but are preferably disposed in pairs on opposite sides of a crank-shaft and inclined at an angle of approximately 45°; this arrangement being preferred in order to facilitate the connections of a system of intercommunicating passageways leading from one cylinder to another, and so that the pistons will be disposed over the inlet ports on the underside of the cylinder.

For the purpose of illustration, the four engine cylinders, although corresponding in construction, are indicated in the accompanying drawings by reference characters A—B—C and D, to facilitate the explanation of the operation of the engine. As the construction of the engine cylinders A—B—C and D, the pistons therein, and the arrangement of ports is practically identical, the description of the construction of one of the engine cylinders will be confined to the one designated as A. This engine cylinder A is constructed with an interior having two diameters to form communicating chambers 2 and 3, the smaller of which, indicated at 2, is uppermost and contains a piston 4 of a length approximating one-half the length of the chamber 2, which length is substan-

tially the length of stroke of the piston. The enlarged lower chamber 3 of the engine cylinder contains a piston 5 which connects with the piston 4 by means of a hollow stem 6; the pistons 4 and 5 and the stem 6 being preferably formed in one integral structure. The piston 4 is pivotally attached to a piston rod 7, which leads to and connects with a crank 8 on a crank-shaft 9, revolvably mounted in suitable bearings in a crank-case 10. Formed in the walls of the upper chamber 2 is a vertically extending inlet port 11, which opens into the chamber 2 at a point immediately below the piston 4 when the piston is in its uppermost position; the port 11 opening into the space formed between the upper piston 4 and the lower piston 5 and surrounding the stem 6. Connecting with the outer portion of the port 11 is an inlet port 12, which is separated from the inner portion of the port 11 by means of a horizontally extending partition 13; the port 12 opening into the upper chamber 2 at a point above the upper end of the piston 4 when the latter is in its lowermost position.

Opening into the chamber 2, at a point diametrically opposite the port 12, is an inlet port 14, the upper wall of which is disposed on a plane slightly above the upper wall of the inlet port 12. The port 14 opens into a passage 15, leading to and opening into the lower chamber 3 above the piston 5 therein. An intake port 16, connecting with a carburetor of any suitable construction, opens to the upper chamber 2 at a point on a plane with the port 11, as shown in Fig. 4. An exhaust port 17 leads from the chamber 2 at a point immediately above the upper end of the piston 4 when the latter is in its lowermost position; the lower wall of the exhaust port 17 being on a plane with the lower walls of the ports 12 and 14, while the upper wall of exhaust port 17 is disposed on a plane slightly above the upper wall of the port 14. Opening into the chamber 3, above the piston 5, is an intake and discharge port 18, which port communicates with the ports 11 and 12 on an adjacent engine cylinder, as will presently be described.

The cylinders A and B are disposed on opposite sides of the crank-shaft 9, as shown in Fig. 12, and the connecting rods 7 of the pistons 3 and 5 of the cylinders A and B connect with the crank 8 on the crank-shaft; the engine cylinders A and B being off-set in relation to each other on a horizontal plane to permit of this connection.

The cylinders C and D are arranged on opposite sides of the crank-shaft 9; the cylinder C being on the same side with the cylinder A, and the cylinder D on the same side with the cylinder B, Fig. 7; the cylinders C and D being off-set in relation to

each other so that the pistons therein may be connected to a crank 8' on the crank-shaft 9 which extends in a direction opposite to that of the crank 8. The cylinders A and B are in a different plane transverse to the shaft 9 from the cylinders B and C, as indicated by the broken lines e and f, Fig. 7, and the crank-shaft 9 is off-set from the line of intersection of the axes of the engine cylinders. This arrangement is especially shown in Figs. 12 and 13, and is designed for the purpose of disposing the pistons in the engine cylinders in such relation to the cranks as to cause the impulse of the pistons to act on the cranks after the latter have passed their centers.

An important feature of this invention resides in the manner of connecting the ports, previously described in reference to the engine cylinder A, to the corresponding ports on the cylinders B and D, which connections are particularly shown in Figs. 7 to 11, inclusive. The intercommunication of the ports is as follows: Leading from the ports 11 and 12 on the cylinder A is a conduit 20, which connects with the port 18 on the cylinder D. The ports 11 and 12 on the cylinder B open to a conduit 21 connecting with the port 18 on the cylinder A; ports 11 and 12 on the cylinder C open to a conduit 22 leading to the port 18 on the cylinder B; and the ports 11 and 12 on the cylinder D open to a conduit 23 leading to the port 18 on the cylinder C. The exhaust ports 17 in the several cylinders connect with exhaust pipes 24 which lead to any suitable point of discharge.

A complete cycle of operation of the engine will now be described: Assume the parts to be in the position shown in Figs. 8, 12 and 13 (the positions indicated in Figs. 12 and 13 corresponding to positions shown in Fig. 8), with the pistons 4 and 5 in the chambers 2 and 3 of the cylinder A in their uppermost position and about to move on the downward stroke; the pistons in the cylinder B in an intermediate position on the upward stroke; the pistons in the cylinder C in the lowermost position about to move on the upward stroke, and the pistons in the cylinder D in an intermediate position on the down stroke as indicated by the arrows in Fig. 8. When the piston 4 is in its uppermost position the inlet ports 12 and 14, and the exhaust port 17 are closed; when the piston 4 is in its intermediate position, either on its upward or downward stroke, the inlet ports 11, 12, 14 and 16, and the exhaust port 17 are closed, and when the piston 4 is in its lowermost position the inlet ports 11 and 16 are closed, while the inlet ports 12 and 14 and the exhaust port 17 are open. The piston 4 in moving to its uppermost position compresses a charge of explosive mixture in the upper end of the

chamber 2 in the engine cylinder A, the charge being delivered to the chamber 2 through the ports 12 and 14 when the piston 4 is in its lowermost position, as will be later described. The compressed explosive gases in the engine cylinder A, above the piston 4, are exploded by an electric spark or in any suitable manner, the explosion and consequent expansion of the charge acting to force the piston downward and thereby rotate the crank-shaft 9 in the direction of arrow *g*, in Fig. 12; an explosive charge having previously been exploded in the upper end of the chamber 2 in the engine cylinder D, above the piston 4 therein, to force the piston downward and thereby rotate the crank-shaft 9, through the crank 8', in the direction of arrow *h* in Fig. 13.

The explosion of the gases in the engine cylinder A takes place immediately after the piston 4 has started on its downward stroke, so that the pressure will operate on the crank 8 after the latter has passed out of alignment with the piston rod 7 and the center of the shaft 9. The downward stroke of the piston 4 in the engine cylinder A, rotating the crank 8 in the direction of arrow *g* in Fig. 12, causes the piston 4 in the engine cylinder B to move upward on its compression stroke to compress a charge in the upper portion of the chamber 2 in the engine cylinder B. The piston 4 in the engine cylinder C will also move upward on its compression stroke, on the downward movement of piston 4 in the cylinder A, and the piston 4 in the cylinder D will move downward on its explosion stroke. The piston 5 in the engine cylinder D, moving downward with the piston 4, operates on the latter part of its stroke in conjunction with the piston 5 in the cylinder A, to draw a charge of explosive mixture from a carburetor through the pipe 19 and inlet port 16 in A, which charge is drawn into the space between the piston 4 and the piston 5 in the engine cylinder A as these pistons 4 and 5 move downward. The piston 4 in the cylinder B, on moving upward, opens the port 11 and causes a volume of explosive mixture previously drawn into the space above the piston 5 in the cylinder B to pass through the port 11, conduit 21 and port 18 into the engine cylinder A, above the downwardly moving piston 5 in the latter; the upward movement of the piston 5 in the engine cylinder B also causing a volume of the explosive mixture thereabove to pass through the port 18 in the cylinder B, through the conduit 22, into the upper chamber 2 of the engine cylinder C, through the port 12, above the piston 4, which piston is now in its lowermost position in the cylinder C. The discharge of the explosive mixture from the chamber 3 in the cylinder B, into the cylinder A, above the piston 5, as occasioned by the upward

movement of the piston 5 in the cylinder B, acts to break the suction above the piston 5 in the cylinder A, excepting such as is occasioned by the downward movement of the piston 5 in the cylinder D, on the lower half of its stroke. The charges thus drawn into the chamber 3 in the cylinder A and the chamber 3 in the cylinder D are heated by contact with the piston stem 6 in the cylinder A. The piston 5 in the engine cylinder C, on its initial upward movement, causes a discharge of a portion of the explosive mixture thereabove through the conduit 15 and port 14 into the upper chamber 2 of the cylinder C, above the piston 4 therein; the explosive mixture above the piston 5 in the engine cylinder C, being previously drawn into the lower chamber 3 of the cylinder C on the down stroke of the piston 5.

From the foregoing it will be seen that the explosion chamber above the piston 4 in the engine cylinder C will be charged with an explosive mixture, which will be delivered through the ports 12 and 14, by the upward movement of the pistons 5 in the cylinders B and C; the intrushing explosive mixture, striking against a deflector 25 on the upper end of the piston 4, acting to force the previously burned charge downwardly and out the exhaust port 17 in the engine cylinder C. This having occurred, the pistons 4 and 5 in the engine cylinder C will move upward on their up-stroke to the intermediate position, as indicated in Fig. 9; the pistons in the cylinder B coming to their uppermost positions, and the pistons in the cylinder D to their lowermost positions, while the pistons in the cylinder A will be in their intermediate positions and moving downward. The piston 4 in the engine cylinder C in moving upward closes ports 12, 14 and 17, and the piston 5 in the engine cylinder C operates to force a portion of the explosive charge thereabove through the port 18 in the engine cylinder C and conduit 23 into the engine cylinder D, through the port 12, above the piston 4, which is now in its lowermost position. When the piston 4 in the engine cylinder C has moved upward a sufficient distance to partially open the port 11, the piston 5 in the cylinder C will act to deliver a portion of the explosive charge thereabove through the port 11, conduit 22 and port 18 in the engine cylinder B, into the space above the piston 5 in the latter cylinder, which piston is about to move on its downward stroke. The previous upward movement of the piston 4 in the engine cylinder B compressed the explosive mixture in the upper chamber 2 of the cylinder B, which mixture is then exploded to cause the pistons 4 and 5 in the cylinder B to move on the down-stroke. The piston 5 in the engine cylinder A, on moving down the latter half of its stroke, acts to draw a charge from

the carbureter through the port 16 in the engine cylinder B, through the port 11 and the cylinder B, and the conduit 21, connecting with the port 18 in the engine cylinder A.

When the piston 4 in the engine cylinder C is in its uppermost position, as shown in Fig. 10, the compressed explosive mixture above the piston 4 is exploded to force the pistons 4 and 5 downward. The pistons 4 and 5 in the engine cylinder A will then move upward to deliver an initial charge into the explosion chamber above the piston 4 therein, simultaneous with a charge which will be delivered from the engine cylinder D through the conduit 20 and the port 12. The piston 5 in the engine cylinder B, on the latter half of its down-stroke, will draw a charge through the conduit 22 from the space above the piston 5 in the cylinder C.

When the piston 4 in the cylinder D is in its uppermost position, as shown in Fig. 11, the compressed explosive mixture thereabove is exploded to force the pistons 4 and 5 in the cylinder D downward; the downward movement of the piston 5 in the cylinder D operating to draw a charge through the conduit 20 from the lower chamber 3 of the cylinder A, above the piston 5 therein, through the port 11 in the cylinder A. The piston 5 in the engine cylinder C, on moving downward on the latter half of its stroke, will operate to draw a charge from the carbureter through the port 16 in the cylinder D. The pistons 4 and 5 in the engine cylinder B, will now, on moving up from their lowermost positions, deliver an initial charge to the upper chamber 2 of the cylinder B, through the port 14; the piston 5 in the cylinder A also forcing a quantity of explosive mixture into the chamber 2 in the cylinder B.

From the foregoing it will be seen that on the initial upward movement of the pistons 4 and 5 a partial charge will be delivered above the piston 4 into the chamber 2, from the chamber 3, by the upward movement of the piston 5; a charge also being delivered through the inlet port 12 by the upward movement of the piston 5 in an adjacent cylinder; the piston 4 closing the port 12 before the port 14 is entirely closed, and the exhaust port 17 remaining open until after the port 14 has been closed to insure a thorough scavenging of the burned gases by the inrushing fresh charge. The upward movement of the piston 5 also acts, during an intermediate portion of its upward stroke, to deliver a quantity of the explosive mixture through the port 12 of an adjacent cylinder, and on the upper portion of the stroke delivers the explosive mixture into the chamber 3 above the piston 5 of an adjacent cylinder. When the piston 5 starts on its down-stroke, the suction thereabove is

broken by the delivery of the explosive mixture thereabove, by the upward movement of a piston 5 in an adjacent cylinder; the space above the piston 5 on the first portion of its downward stroke being filled by the mixture delivered from an adjacent cylinder. As the piston 5 moves on the latter portion of its downward stroke, the remainder of the chamber 3 is filled from the carbureter connecting with an adjacent cylinder. By this construction a continuous, uninterrupted flow of the explosive mixture from the carbureter is obtained. This construction also causes the cold explosive mixture after being drawn from the carbureter to be mixed with a heated volume of explosive mixture in a chamber 3 before being discharged into the explosion chamber 2.

It will be observed that the explosive mixture will not be compressed by the pistons 5, but will be moved on the up-stroke of the pistons into the chamber 2 at approximately atmospheric pressure; and that the mixture will be compressed by the pistons 4 only on the up-stroke of the latter.

Having thus described my invention, what I claim and desire to secure by Letters Patent is:

1. In an internal combustion engine, a plurality of cylinders each having superposed communicating chambers of different diameters, connected pistons in said chambers, a feed port and an intake port opening to the space between the pistons, an inlet port connecting with said intake port opening to the upper chamber above the upper piston, a passage leading from the lower chamber and opening into the upper chamber on a plane above the inlet port, a port in the lower chamber above the piston therein communicating with the combined inlet and intake ports of an adjacent cylinder, and an exhaust port in the upper chamber.

2. An internal combustion engine comprising a series of four cylinders, A—B—C and D, each of said cylinders being formed with superposed axially connected chambers of different diameters, a piston in the upper chamber and a piston in the lower chamber connected together, a feed port and an intake port opening to a space between the pistons, an inlet port opening to the upper chamber above the piston therein, a passage leading from the lower chamber opening into the upper chamber above the piston therein, an open port in the lower chamber above the piston therein, an exhaust port in the upper chamber, the open port in the lower chamber of the cylinder A communicating with the inlet and intake ports of the cylinder B, the open port in the lower chamber of the cylinder B communicating with the inlet and intake ports of the cylinder C, the port in the lower chamber of the cylinder C communicating with the in-

take and inlet ports of the cylinder D, and the port in the lower chamber of the cylinder D communicating with the inlet and intake ports in the cylinder A.

- 5 3. An internal combustion engine comprising four cylinders, A—B—C and D, a pair of superposed pistons in each of said cylinders, a feed port connecting with a carbureter opening into a space between the 45
10 superposed pistons, a passage leading from above the lower piston and opening above the upper piston when the latter is in its lowermost position, an inlet port opening above the upper piston, an intake port opening 50
15 above the lower piston adapted to be closed by the upper piston, an open port above the lower piston, the open port of the cylinder A communicating with the intake and inlet ports of the cylinder B, the open 55
20 port of the cylinder B communicating with the intake and inlet ports of the cylinder C, the open port of the cylinder C communicating with the inlet and intake ports of the cylinder D, and the open port of the cylinder 60
25 D communicating with the intake and inlet ports of the cylinder A.
4. An internal combustion engine comprising four cylinders, A—B—C and D, a pair of superposed pistons in each of said cylinders, a feed port opening to a space between the superposed pistons connecting with a carbureter, a passage leading from above the lower piston and opening above the upper piston when the latter is in its lowermost 65
30 position, an inlet port opening above the upper piston, an intake port opening above the lower piston adapted to be closed by the upper piston, an open port above the lower piston in the cylinder A communicating 70
35 with the intake and inlet ports in the cylinder B, an open port above the lower piston in the cylinder B communicating with the intake and inlet ports of cylinder C, an open port in the cylinder C communicating with the inlet and intake ports of the cylinder D, and an open port above the lower piston in the cylinder D opening to the intake and inlet ports of cylinder A.
- 40 A communicating with the intake and inlet ports of the cylinder B, the open port of the cylinder B communicating with the intake and inlet ports of the cylinder C, the

open port of the cylinder C communicating with the inlet and intake ports of the cylinder D, the open port of the cylinder D communicating with the intake and inlet ports of the cylinder A, exhaust ports in each of said cylinders; the pistons in the cylinders acting to open and close the ports and transfer the impelling medium.

5. An internal combustion engine comprising a series of four cylinders, A—B—C and D, a pair of superposed connected pistons of different diameters in each of said cylinders, a feed port connecting with a source of supply opening to a space between the superposed pistons in each of the cylinders, an exhaust port opening above the uppermost piston when the latter is in its lowermost 60 position, an intake port opening to the space between the pistons when in their uppermost position, an inlet port above said intake port opening above the uppermost piston when in its lowermost position, a passage above 65 the lower piston opening above the uppermost piston when the latter is in its lowermost position, an open port above the lower piston in the cylinder A communicating with the intake and inlet ports in the cylinder B, an open port above the lower piston in the cylinder B communicating with the intake and inlet ports of cylinder C, an open port in the cylinder C communicating with the inlet and intake ports of the cylinder D, and an open port above the lower piston in the cylinder D opening to the intake and inlet ports of cylinder A.

In testimony whereof I have hereunto set my hand in the presence of two subscribing 80
witnesses.

ANTON A. RUEGG.
